UNITED STATES PATENT OFFICE.

JOHN SIEBEL, OF OSKALOOSA, IOWA.

FLOOR-TILE.

SPECIFICATION forming part of Letters Patent No. 254,396, dated February 28, 1882.
Application filed October 5, 1881. (No model.)

To all whom it may concern:

Be it known that I, JOHN SIEBEL, of Oskaloosa, in the county of Mahaska and State of Iowa, have invented certain new and useful 5 Improvements in Floor-Tiles; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan view of one of my improved floor-tiles. Fig. 2 is a horizontal sectional view 15 of the same, and Fig. 3 is a vertical transverse sectional view.

Corresponding parts in the several figures are denoted by like letters of reference.

This invention relates to wooden tiles for 20 flooring purposes; and it consists in certain improvements in the construction of the same, which consist essentially in inclosing within a common frame a number of smaller tiles or blocks, as will be hereinafter fully described, 25 and particularly pointed out in the claim.

In the drawings hereto annexed, A represents a rectangular frame consisting of sides B B and ends C C, which latter are notched into the side pieces, as shown.

30 D D are square wooden blocks or tiles, of which any suitable number may be fitted within the frame A, which is made of a size to correspond. The said blocks may be made of the same or of different kinds of wood, in which lat- 35 tercase a fine effect in coloring may be produced; but in any case the grain of each individual block must be at an angle to that of the block or tile next adjoining, for the obvious reasons of preventing warping, increasing the durabil- 40 ity, and promoting the handsome and attract-

ive appearance of the complete tile. The edges of the blocks D and of the inner sides of the frame are provided with horizontal incisions or kerfs K to accommodate strips S, of sheet metal or other suitable material, which shall serve to unite the blocks firmly to prevent the passage of moisture and to assist in making a durable and attractive article.

The strips S, it will be observed, also serve to hold or bind the blocks D in the frame, from 50 which, when said frame has been joined, they cannot be removed.

By this invention handsome and valuable flooring-tiles may be produced from material which would otherwise have but little com- 55 mercial value, and this at an insignificant cost.

I am aware of the patent to Siemroth, Sep- 60 tember 10, 1878, which shows center and border tiles having kerfed edges to receive the connecting-strips, and secured to the floor by metallic strips or staples. This construction I do not claim; but,

Having thus described my invention, I claim and desire to secure by Letters Patent of the 65 United States—

As an article of manufacture, a floor tile consisting of a number of blocks, D, arranged within a frame, A, the edges of said blocks and the inner edges of the ends and sides of said frame being provided with recesses or kerfs K for the sheet-metal strips S, which serve to 70 make tight joints and also to secure the blocks in the frame, substantially as set forth.

In testimony that I claim the foregoing as my own I have hereunto affixed my signature 75 in presence of two witnesses.

JOHN SIEBEL.
